UNITED STATES PATENT OFFICE.

FRANK YOKEL, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF PENNSYLVANIA.

LIGHTING-FIXTURE.

1,349,485.

Specification of Letters Patent. Patented Aug. 10, 1920.

Application filed November 26, 1917. Serial No. 203,891.

To all whom it may concern:

Be it known that I, FRANK YOKEL, a citizen of the United States, residing at Pittsburgh, in the county of Allegheny and State 5 of Pennsylvania, have invented certain new and useful Improvements in Lighting-Fixtures, of which the following is a specification.

My invention relates to lighting fixtures, 10 and more particularly to semi-indirect electric light fixtures employing a bowl for the reception of the lamp and a reflector or shade above the bowl.

The class of lighting fixtures to which my 15 invention relates are especially adapted for lighting large rooms, halls, stores, hospitals, etc., and among the objects of the present invention are to so shape and position the bowl and reflector as to provide a greater 20 diffusion of the light rays than has heretofore been possible in fixtures of this character; to provide new and improved bowl and reflector supporting means, and an improved construction and combination of 25 parts, all as fully hereinafter described and claimed.

In the accompanying drawings, which illustrate an application of my invention,

Figure 1 is a vertical sectional view of 30 my invention;

Figs. 2 and 3 are perspective views of the bowl reflector supporting means employed; and

Fig. 4 is a side elevational view showing 35 the supporting means assembled with portions of rods projected therefrom.

Referring to the drawings, 2 designates an electric lamp disposed within an open-top bowl 3. The lamp socket 4 is secured to a 40 threaded plug 5 having a ring 6, the latter being connected with a chain 7 by means of which the lighting fixture is suspended.

The bowl 3 together with a reflector or shade 8 is supported by common supporting 45 means including, as illustrated and as preferred, two telescoping members 9 and 10. The top portion 11 of member 9 is formed with an opening 12 through which the plug 5 is passed to engage the upper end of the 50 socket. The construction of member 9 is particularly shown by Fig. 2, and as illustrated, includes a series of outwardly projecting pins 14 and a spring arm locking member 15, the latter having a pin 16.

55 The second member entering into the com-

mon supporting means is provided with a series of bayonet slots 17 and a series of vertically extending slots 18. Said member is further provided with an annular flange 19 disposed at the bottom of the 60 member and adapted, as shown by Fig. 1, to support the reflector 8. The annular flange 19 is formed with openings 20 through which a series of supporting rods 21 are entered, said supporting rods at their upper ends being bent as shown at 22.

The lower ends of the supporting rods 21 are secured to the bowl by means of an adjustable screw device 23. The inner end of the screw device 23 has an eye 24 adapted to 70 engage the lower end of the supporting rod and the outer shank portion thereof is provided with a knob 25. 26 designates a washer interposed between the interior face of the bowl and the eye of the screw 23.

In assembling the supporting means, member 9 is inserted within member 10 with the pins 14 entered in the bayonet slots 17. After the pins are entered in said slots 17, the member 9 is turned sufficiently to permit the pin 16 of the locking member 15 to enter a vertically extending slot 18, thereby locking the two members against relative 80 rotational movement while assembled.

It will be understood that by the employment of the locking means in connection with the pins and bayonet slots, as described, a construction is provided that will prevent the said members 9 and 10 from being accidentally separated while the lighting fixture 90 is suspended.

Attention is called to the concavo-convex configuration of the glass reflector 8 and its disposition at a considerable distance above the upper end of the open-top bowl. The 95 shape of this reflector and its position relative to the upper end of the bowl provides for a greater diffusion of light rays in fixtures of this character than has heretofore been possible. The concave reflecting surface A of the light diffusing reflector preferably projects beyond the periphery of the upper end of the bowl.

What I claim is:—

1. In a lighting fixture, the combination 105 with an open-top bowl, a glass reflector spaced from the top of the bowl and having a central opening and a concavo-convex reflecting portion extending from the opening with its concave side nearest to and project- 110

ing beyond the periphery of the upper end of the bowl, and common supporting means for the bowl and reflector including telescoping members provided with coöperating pins and slots, the outer of said members having an annular flange, the wall of the reflector opening mounted on the flange, and means connecting the flange and bowl.

2. In a lighting fixture, the combination with an open-top bowl, a glass reflector spaced from the top of the bowl and having a central opening and a concavo-convex reflecting portion extending from the opening with its concave side nearest to and projecting beyond the periphery of the upper end of the bowl, and common supporting means for the bowl and reflector including

telescoping members provided with coöperating pins and slots, and locking means for preventing relative movement of the members after assemblage, the outer of said members having an annular flange, the wall of the reflector opening mounted on the flange, said flange formed with openings and hooked rods entered in said openings at their upper ends, and means connecting the lower ends of the rod and bowl.

In testimony whereof I affix my signature in presence of two witnesses.

FRANK YOKEL.
